UNITED STATES PATENT OFFICE.

FRANK A. SHIMANS, OF CHICAGO, ILLINOIS.

STROPPING-MACHINE.

1,210,222.

Specification of Letters Patent. Patented Dec. 26, 1916.

Application filed April 20, 1916. Serial No. 92,370.

To all whom it may concern:

Be it known that I, FRANK A. SHIMANS, a citizen of the United States, and a resident of the city of Chicago, county of Cook, and 5 State of Illinois, have invented certain new and useful Improvements in Stropping-Machines, of which the following is a specification.

My invention relates to improvements in 10 stropping machines designed for use especially in the sharpening of circular razor blades.

The object of my invention is the production of a device of this character which will 15 be of durable and economical construction and efficient in use.

Other objects will appear hereinafter.

The invention consists in the combinations 20 and arrangements of parts hereinafter described and claimed.

The invention will be best understood by reference to the accompanying drawing forming a part of this specification, and in which,

25 Figure 1 is a front elevation of a stropping machine embodying the invention, Fig. 2 is a side elevation thereof, Fig. 3 is a section taken on line $x-x$ of Fig. 2, and Fig. 4 is a slightly enlarged section taken on line 30 $y-y$ of Fig. 1.

The preferred form of construction, as 35 illustrated in the drawing, comprises an elongated sharpening element 1 in the form of a leather strap or the like which is provided at its upper end with a wire loop 2 for attaching the same to a hook or other suitable supporting device. The lower end of said sharpening element is formed to constitute a handle 3. At the upper and lower ends of 40 the sharpening element are provided forwardly and laterally projecting arms 4 and 5 respectively, the arms 4 being formed integral with the loop 2, and the arms 5 being the ends of a reinforcing wire which is embedded in the handle 3. The arms 4 and 5 45 serve as supports for flexible guides 6 which extend longitudinally of the sharpening element, parallel with the longitudinal edges thereof.

50 Mounted for longitudinal movement at the front side of the sharpening element 1 is a carriage 7 provided at its outer end with a handle 8 whereby said carriage may be manually operated. At the sides of said 55 carriage are provided channel pulleys 9 which engage with the guides 6 whereby said

carriage is guided in its longitudinal movement. The pulleys 9 also constitute gears, being provided at their peripheries with teeth which engage with gears 10 provided 60 at the ends of a shaft 11 mounted in the carriage 7. The shaft 11 is adapted to support the circular razor blade 12 which it is desired to sharpen, the blade being removably secured thereto by means of a bolt and nut 65 fastening 13. To accommodate the blade, one side of said shaft is flattened, as clearly shown in Fig. 4. The fastening 13 permits of rotatable adjustment of the blade, which adjustment may be effected by means of an 70 arm 14 which is mounted at 15 in the carriage for universal pivotal movement. The inner end of arm 14 is provided with a shoe 16 of rubber or other suitable material which is adapted for engagement with the blade to 75 effect partial rotation of the same upon manipulation of the outer end of said arm.

Provided at the upper and lower ends of the carriage 7 are inwardly projecting arms 17 which engage under the longitudinal 80 edges of the sharpening element 1 in order to transversely curve said element to conform more nearly with the curvature of the periphery of the blade during operation of the carriage, as will be readily understood. 85

In the operation of the device, the blade having first been secured to the shaft 11, it is only necessary to manually reciprocate the carriage. When this is done, it will be seen, that the contact of the pulleys 9 with the guides 6 will exert a rotary pressure upon the shaft 11 which will serve to press one side of the periphery of the blade into engagement with the sharpening element, the side thus pressed into engagement with the 90 sharpening element being the remote side of the blade relative to the direction in which the carriage is moved. For instance, when the carriage is moved downwardly, the position of the blade is that shown in Fig. 4. In the upward movement of the carriage the 95 rotary pressure exerted upon the shaft 11 will be such as to press the opposite or lower side of the blade into engagement with the sharpening element. The respective ends of the guides 6 are inclined outwardly or away from the sharpening element so that as the carriage approaches the terminals of its movement, the same will automatically be moved away from the sharpening element 100 and thus permit of revolving of the blade in order to present the opposite side of the same 105 110

to the action of the sharpening element upon the return movement of the carriage. The blade is rotatably adjusted to present new portions of the periphery of the same for contact with the sharpening element by simply manipulating the arm 14, as above described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A stropping machine comprising an elongated flexible sharpening element; longitudinally movable means for supporting a razor blade and holding the same in engagement with said sharpening element; and means carried by the blade supporting means for curving said sharpening element transversely, substantially as described.

2. A stropping machine comprising an elongated flexible sharpening element; a carriage movable longitudinally of said sharpening element; longitudinally extending guides for coöperation with said carriage; means on said carriage for supporting a razor blade and holding the same in engagement with said sharpening element; and means on said carriage engaging with said sharpening element for imparting transverse curvature to said sharpening element in the movement of said carriage, substantially as described.

3. A stropping machine for the sharpening of circular blades comprising an elongated flexible sharpening element; a carriage movable longitudinally of said sharpening element; longitudinally extending guides for coöperation with said carriage; means on said carriage for supporting a razor blade and holding the same in engagement with said sharpening element; and inwardly extending fingers on said carriage engaging under the longitudinal edges of said sharpening element for transversely

curving said sharpening element adjacent the carriage, in the movement of the latter, to conform with the curvature of the periphery of the blade, substantially as described.

4. A stropping machine for the sharpening of circular blades comprising an elongated flexible sharpening element; a carriage movable longitudinally of said sharpening element; longitudinally extending guides for coöperation with said carriage; means on said carriage for supporting a razor blade and holding the same in engagement with said sharpening element; and inwardly extending fingers on said carriage engaging under the longitudinal edges of said sharpening element for transversely curving said sharpening element adjacent the carriage, in the movement of the latter, to conform with the curvature of the periphery of the blade, said guides being inclined outwardly at their ends to adapt the same, upon said carriage approaching the ends of said sharpening element, to move the same outwardly from said element to allow for revolving of the blade, substantially as described.

5. A stropping machine for the sharpening of circular blades comprising an elongated sharpening element; a carriage movable longitudinally of said sharpening element; means on said carriage for rotatably supporting a razor blade and holding the same in engagement with said sharpening element; and means for rotatably adjusting said blade, substantially as described.

6. A stropping machine for the sharpening of circular blades comprising an elongated sharpening element; a carriage movable longitudinally of said sharpening element; means on said carriage for rotatably supporting a razor blade and holding the same in engagement with said sharpening element; and a pivotally mounted manually-operable arm for rotatably adjusting the blade, substantially as described.

In testimony whereof I have signed my name to this specification in the presence of two subscribing witnesses.

FRANK A. SHIMANS.
